US0D1038890S

(12) **United States Design Patent** (10) Patent No.: **US D1,038,890 S**
(45) Date of Patent: ** Aug. 13, 2024

(54) **CONNECTOR**

(71) Applicant: **SHENZHEN YONGCHUANGCHENG TECHNOLOGY CO., LTD.**, Shenzhen (CN)

(72) Inventor: **Lijuan Yang**, Shenzhen (CN)

(73) Assignee: **SHENZHEN YONGCHUANGCHENG TECHNOLOGY CO., LTD.**, Shenzhen (CN)

(**) Term: **15 Years**

(21) Appl. No.: **29/911,946**

(22) Filed: **Sep. 12, 2023**

(51) LOC (14) Cl. **13-03**

(52) U.S. Cl.

USPC **D13/133**

Assistant Examiner — Denis Houyoux

CLAIM

The ornamental design for a connector, as shown and described.

DESCRIPTION

FIG. 1 is a perspective view of a connector showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the connector that form no part of the claimed design.

1 Claim, 8 Drawing Sheets
